UNITED STATES PATENT OFFICE.

ULRIC ST. MARIE AND GEORGE BERNIER, OF PUTNAM, CONNECTICUT.

KNEELING STOOL.

Application filed November 5, 1924. Serial No. 747,921.

To all whom it may concern:

Be it known that we, ULRIC ST. MARIE and GEORGE BERNIER, citizens of the United States, residing at Putnam, in the county of 5 Windham and State of Connecticut, have invented certain new and useful Improvements in Kneeling Stools, of which the following is a specification.

This invention relates to kneeling stools 10 or boards employed in churches and associated with the pews, and has for one of its objects to simplify and improve the construction and increase the efficiency and utility of devices of this character.

Another object of the invention is to 15 provide a device of this character which may be associated without material change with pews of various forms and sizes, and which automatically assumes a vertical or 20 inoperative position when released.

With these and other objects in view the invention consists in certain novel features of construction as hereinafter shown and described and then specifically pointed out in 25 the claims, and in the drawings illustrative of the preferred embodiment of the invention.

Figure 1 is a rear view of a conventional church pew with the improved kneeling 30 stool associated therewith.

Figure 2 is a transverse section, enlarged, on the line 2—2 of Figure 1, looking in the direction of the arrow.

Figure 3 is a detached perspective view 35 of the body portion of the improved device.

Figure 4 is a sectional detail, illustrating a modification in the construction.

The improved device comprises a body portion 10 of any desired material length 40 and width but preferably of wood and adapted, generally, to extend between the pew ends, or between the pew ends and the intermediate support of the seat and back portions of the pew.

For the purpose of illustration the improved device is shown extending between the ends 11—12 of a conventional pew, the seat of the pew being indicated at 13 and the back at 14.

Attached to the body 10 at the ends are 50 metal members 15 and 16 with the major portions at one side of the longitudinal center of the body, the largest ends to operate as balancing weights, as hereinafter explained.

Projecting respectively from the members

15 and 16 are pivot pins or studs 17 and 18, the latter located at the opposite side of the longitudinally central axis of the body, and toward the lighter side of the members 15 60 and 16, as shown.

Disposed within the space between the pew ends are standards 19 and 20 in which the studs 17 and 18 are received, as shown in Figure 1. By this means the body 10 65 and its attachments 15 and 16 is swingingly supported between the standards, and normally held in vertical position as shown in Figure 1, by the extra weight at one end of the members 15, 16 as will be obvious. 70

The standards 19 and 20 are shown attached to the confronting faces of the pew ends, but it will be understood that the standards can be supported in any other desired manner, or the pew ends may be employed to support the studs, as shown in 75 Figure 4.

Attached to the rear face of the body 10 is a bracket 21 having perforated ears to receive a pivot 22 by means of which a prop 80 or leg 23 is swingingly coupled to the body, and adapted to bear upon the floor, indicated at 24, when the body is turned into horizontal position as shown in Figure 2.

When the body is in its upper or inoperative position, as shown in Figures 1 and 2, the prop 23 automatically assumes a position in parallel relation to the body, and also automatically assumes the position shown in Figure 2, when the body 10 is 90 moved into horizontal position or when the body is turned downwardly, and thus operates to hold the body from moving beyond a horizontal position.

Cushion elements 25 and 26 of rubber or 95 the like are attached respectively to the body 10 and to the floor 24, as shown, to receive the impact of the prop both in open and closed position, to prevent noise when the device is operated.

When the occupant of the pew desires to use the device, the body is turned down manually against the resistance of the weights 15 and 16 and until the body is in horizontal position with the prop 23 bearing 105 on the cushion 26, when the weight of the kneeling person will hold it in horizontal position. As the kneeling person rises and removes his weight from the body 10, the weights 15 and 16 will overbalance the body 110 and return it to vertical position as shown in Figure 1.

The body 10 when in vertical or inoperative position will be out of the path of persons entering or leaving the pew, and will also be out of the way of brooms, mops, or 5 other cleaning implements.

The preferred embodiment of the invention is disclosed in the drawings and set forth in the specification, but it will be understood that modifications within the scope 10 of the claimed invention may be made in the construction without departing from the principle of the invention or sacrificing any of its advantages.

Having thus described the invention what 15 is claimed is:

1. A device of the class described comprising a body having its ends directed reversely oblique to the longitudinal axis of the same, extensions to said body and attached to the ends thereof, said extensions 20 being of heavier material than the material of the body with the confronting edges directed reversely oblique to correspond to and engage the oblique ends of the body and 25 with their outer edges at right angles to the

longitudinal axis of the body and of the extensions, pins extending from said extensions and disposed toward the narrower and lighter side of the same, and supports to rotatively receive said pins, whereby the 30 heavier portions of the extensions operate as weights to cause the body to be retained normally in vertical position by gravity.

2. A device of the class described comprising an intermediate body extensions of heavier material than the body attached to the ends of the same and forming continuations thereof, pins extending from said extensions and disposed at one side of the longitudinal center of the body and of the extensions, and stationary supports having seats to receive said pins, whereby the extensions operate as weights to cause the body and its extensions to be retained in vertical 40 position by gravity.

45 In testimony whereof, we affix our signatures hereto.

ULRIC ST. MARIE.
GEORGE BERNIER.
